UNITED STATES PATENT OFFICE

1,971,181

GROUND NOISE ELIMINATION

Charles D. Greentree, Schenectady, N. Y., assignor
to General Electric Company, a corporation of
New York

Application April 12, 1930, Serial No. 443,875

7 Claims. (Cl. 179—100.3)

My invention relates to the making of photographic sound records which are adapted for use in the reproduction of the recorded sound. In the reproduction of sound from a photographic film record as heretofore made, whether the record be of the variable density type or the variable width type, there is usually in addition to the recorded sound a certain amount of so called "ground noise". Such noise being of a substantially constant intensity of volume is not noticeable as long as the recorded sound is of the usual volume but whenever the sound volume reaches a low value the ground noise in comparison becomes the more prominent. Ground noise is particularly noticeable, for example, during very soft passages in musical reproductions and also before the recorded sound comes on and after it ceases. It is known that a considerable part of the ground noise heard when a film record is reproduced is a result of striations, scratches and dirt on the relatively clear portions of the record where the light passes freely into the photo-electric cell. Various arrangements have been proposed for reducing the ground noise from film sound records by the use of supplementary apparatus applied to the sound recorder for modifying the record in the original recording. In certain cases it is found to be objectionable to add anything to the recorder which will add complication thereto or require any additional attention by the operator, this being particularly true in the case of portable instruments. It is the object of my invention to provide an improved method and apparatus for reducing, if not eliminating, the cause of the objectionable ground noise in a copy of the sound record.

My invention will be better understood from the following description taken in connection with the accompanying drawing, and its scope will be pointed out in the appended claims.

Referring to the drawing, Fig. 1 is a diagrammatic view of one form of apparatus embodying my invention; Figs. 2 and 3 are detail views thereof and Figs. 4 and 5 are enlarged views of fragments respectively of an original sound record film and a copy thereof made in accordance with my invention.

In illustrating my invention I have shown apparatus for making the photographic copy from a previously made photographic film record which record may be an original sound record or a duplicate thereof such for example as that made by printing or by re-recording from a film, a phonographic or a magnetic rec-

ord. Moreover the sound record to be copied may be of either the variable density type or the variable width type.

In Fig. 1 I have shown the film 1 being unwound from the roll 2 and being wound up on the roll 3, which film for example, may be an original negative sound record film, a fragment of which appears in Fig. 4. At 4 is shown the sensitive film being unwound from the roll 5 and wound up on the roll 6 upon which film the sound record on film 1 is being printed. The particular form of printing apparatus employed forms no part of and is immaterial to my present invention. Various well known film printers may be used. For convenience of illustration I have shown in a diagrammatic manner a printer of the contact type wherein the two films 1 and 4 pass in contact beneath the printing light. In this printer the two films are shown moved by engagement with the common sprocket wheel 8 while passing between members 9 and 10. Light from the source 11 passes through the opening 12 to the films. The two films are shown fed to the printer by a common sprocket 14 and are withdrawn from the printer by the sprockets 15 and 16, the driving means for the sprockets being omitted from the drawing. Between sprocket 14 and the printer suitable friction rollers 17 are shown by means of which the films are given the proper tension upon entering the printer.

Between the film roll 2 and the sprocket 14 film 1 passes a gate shown for example as the curved member 19 having the opening 20 arranged opposite the sound record track on the film. At one side of the gate is the light source and optical system 21 by means of which a narrow light beam is projected through opening 20 on the film, the beam forming a line of light 22 on the film, see Fig. 2. Behind the film is the photo-electric cell 24 in a position to receive the light beam as modified by the sound record. Connected with the cell 24 is the amplifier 25, the full wave rectifier 26 and the filter 27 from the latter of which there is received a direct current which varies substantially with the amplitude of the sound waves recorded on film 1. Between film roll 5 and sprocket 14, film 4 passes a gate which is shown for example as the curved member 29 having therein the opening 30 arranged opposite the sound track of film 4. By means of the light source and optical system 31, which for example may or may not be similar to that shown at 21, a light beam is projected through the opening 30 on to the

sound track of film 4. The light thus projected on the film is controlled to give a supplemental exposure of the sound track in accordance with the output of the filter 27 whereby said exposure shall be a minimum when the amplitude of the waves recorded on film 1 have a given maximum value and shall be a maximum when the amplitude of the recorded waves are a minimum. Various means may be employed thus to control the supplemental exposure of the sound track. In the form of my invention illustrated, the sound record being printed is of the variable width type and the amount of supplemental exposure is controlled by the use of a shutter arranged in the path of the light beam and movable transversely of the film in accordance with the output of the filter 27. Referring to Figs. 1 and 3, the shutter 33 is mounted on the arm 34 attached to the coil 35 which is connected with the filter 27 through switch 28. Coil 35 is mounted on pivots 36 within the field of a magnet having pole pieces 37. The small stop pin 38 projecting from the member 29 is positioned in the path of movement of the arm 34 which is yieldingly held against the stop by the coil spring 39. In this position of the shutter substantially one half of the sound track is exposed, or if preferred more than one half may be exposed. Energization of the coil 35 effects a counter-clockwise rotation of the shutter as viewed in Fig. 3 whereby more and more light is cut off depending upon the degree of rotation. In Fig. 4, the negative film 1 has the sound record 40 which in the region indicated by 41 has a very large amplitude and in the region indicated by 42 has zero amplitude corresponding to no sound, the sound track in the latter region being exposed for substantially one half of its width. The positive print 43 made from this negative and illustrated in Fig. 5 shows at 44 the effect of the supplemental exposure. From this figure it will be seen that where the amplitude of the sound waves is a maximum the amount of supplemental exposure is a minimum and where the sound volume is very small or is of zero value the supplemental exposure is the greatest. I prefer to have the two exposures slightly overlap at those times when there is no sound on the record, however, under certain conditions it may be preferable to have them just meet at such times or even to come not quite together thus leaving a narrow clear central line. Inasmuch as the filter circuit introduces a certain electrical time lag in the response of the shutter the supplemental exposing apparatus is spaced from the printer along film 4 a distance which is less than the corresponding distance along film 1 of the optical system 21. This difference in spacing is sufficient, taking into account the film speed, to compensate for the time lag produced by the filter. It may also be varied, if desired, to allow for such recording characteristics as steep wave fronts. My invention as already pointed out above is applicable to the making of copies of sound records of either the variable density type or the variable width type or even to making a copy in accordance with one type from a record made by the other type. In making a variable width type record with apparatus such as I have shown I prefer to have the shadow which is cast on the film by the shutter as sharp as convenient, hence I arrange the shutter as close as practicable to the member 29. In making a variable density record with this appara-

tus, however, I prefer that the shadow shall not be sharp but rather be as uniform as possible across the sound track. For this purpose the shutter would be arranged as close as practicable to the optical system 31 and for maximum effectiveness it obviously would be adjusted to have a swing sufficient substantially to completely cover and uncover the light opening in the end of the optical system. Instead of the shutter construction which I have illustrated for varying the supplemental exposure I may in certain cases prefer to use a well known form of oscillograph or reflecting galvanometer such as is commonly employed in the recording of sound of the variable width record type and as shown for example in the Dimmick Patent 1,820,785, Aug. 25, 1931. For the making of record copies of the variable density type I may also in certain cases prefer to use instead of the shutter apparatus illustrated a light valve such as shown for example in the Wente Patent 1,638,555, August 9, 1927, to produce the desired variation in supplemental exposure of the film copy. It is to be noted that the purpose of the filter 27 is to iron out the waves and to provide for a relatively smooth line of the supplemental exposure. In the event that the light controlling device employed has a low natural period of vibration or period below the audible range, I may dispense with the filter and rely entirely upon such device to give the desired smooth line.

By providing for the elimination of ground noise at the time of making a copy of the sound record, I not only avoid unnecessarily complicating the recording apparatus but I am able to take any sound record with which there is an objectionable amount of ground noise and by making a copy thereof in accordance with my invention to greatly reduce if not to entirely eliminate the ground noise heard when the copy is used to reproduce the sound. In the event that the operator desires to render inoperative the supplemental exposing means at any time he simply opens the circuit by means of the switch 28. Such may be found convenient when the record includes sharp or irregular sounds such as pistol shots. If desired the record film itself may be arranged to control the switch automatically in any well known manner, for example, by the use of notches cut in the edge of the film.

I have chosen the particular embodiment described above as illustrative of my invention and it will be apparent that various modifications may be made without departing from the spirit and scope of my invention which modifications I aim to cover by the appended claims. What I claim as new and desire to secure by Letters Patent of the United States, is:

1. The method of making a sound record copy which is relatively free of the cause of ground noise from a previously made sound record which comprises making a contact print of the sound record, producing a current which varies in accordance with the average amplitude of a number of successive waves of said record and variably exposing the normally clear portion of the print in accordance with said current.
2. In apparatus for making a print film from a sound record film, means for printing the sound record on the print film from the record film, means for producing a current variable in accordance with the average amplitude of a number of successive recorded waves of the rec-

- ord film, means for directing a light beam on the print film to expose the same and means including a shutter responsive to said current for varying the amount of said beam reaching the print film at portions thereof unexposed by said printing means. 5 a light sensitive film, simultaneously translating the record variations of the record film at other successive points into current variations and exposing the sensitive film also at other successive points in accordance with the average amplitude of a number of successive waves of said current. 80
3. In apparatus for making a print film from a sound record film, means for printing the sound record on the print film from the record film, means for producing a current variable in accordance with the average amplitude of a number of successive recorded waves of the record film, means for directing a light beam on an unexposed part of the print film, a shutter in the path of said beam and means responsive to a decrease in said current corresponding to a decrease in said amplitude for moving said shutter in a direction to expose a greater part of said print film unexposed by said printing means. 10 85
4. The method of making a sound record copy which is relatively free from the cause of ground noise from a previously made sound record which comprises exposing a light sensitive strip 15 in accordance with the waves of the sound record, producing a current which varies in accordance with the average amplitude of a number of successive waves of said record, exposing an unexposed part of the strip to light of a uniform intensity and varying the exposed area of the strip in accordance with said current. 90
5. The method of making a sound record copy which is relatively free from the cause of ground noise from a previously made sound record film 20 which comprises printing the sound record from the record film at successive points thereof on 95
- 25 a light sensitive film, simultaneously translating the record variations of the record film at other successive points into current variations and exposing the sensitive film also at other successive points in accordance with the average amplitude of a number of successive waves of said current. 100
- 30 35
6. Apparatus for making a copy of a previously made sound record which copy is relatively free from the cause of ground noise which comprises means for progressively exposing a light sensitive strip in accordance with the variations of said sound record, means for producing a current which varies in accordance with the average amplitude of a number of successive waves of said sound record, a source of light of uniform intensity arranged to expose portions of said strip otherwise unexposed and a shutter responsive to said current for controlling the exposure of the strip by said light. 105
